UNITED STATES PATENT OFFICE.

RICHARD T. SCHOLES, OF HINSDALE, ILLINOIS.

RAIL JOINT.

Application filed October 31, 1925. Serial No. 65,910.

This invention relates to improvements in rail joints.

The object of the invention is to produce a device which will join the abutting ends of two adjacent rails in a firm and secure manner, hold the rails from creeping, secure the device as a whole firmly to the ties upon which it is laid, eliminate or reduce to a negligible quantity all tendency to rattle, have no complicated parts to get out of order, and be durable in track;—in other words, a device which will function as perfectly as is possible.

The invention consists in the devices and combinations of devices illustrated and described, and will be more particularly indicated in the claims appended hereto.

In the accompanying drawings:

Figure 1 is a side view of my rail joint applied to two rail ends and resting upon two ties.

Figure 2 is a plan view of the same.

Figure 3 is an end view showing one rail in vertical section.

Referring to Figures 1, 2 and 3, it will be seen that the rails are indicated at A, the ties at B, the plate on the ties at C, the fish plate, angle bars at D and fastening bolts at E.

The plate.—The rails rest upon the top surface 1, longitudinally of the plate C, which latter is shown as of sufficient length so that it will be supported at its two ends upon two ties in track. This rail bearing surface is cambered, that is to say, is convexly curved from end to end as clearly indicated by the dotted line 2 on Fig. 1. The crown of the camber will preferably be at the median line of the plate C, where the ends 3, 3, of adjacent rails meet intermediate the two ties.

The plate is provided on each of its longitudinal margins with an integral, upwardly directed flange 4, thus giving the plate a channel form in cross-section. It is provided with spike holes indicated by dotted lines 5, Fig. 3.

At diagonally opposite corners of the plate, the flange 4 is cut vertically so as to form a member 6 which may be bent inwardly, towards the rail, as indicated in Figs. 2 and 3, to form an abutting shoulder for the angle plate bars D.

The angle bars.—The bars D are of less length than the plate, and are L-shaped. The vertical arm 7 is provided with a down-

wardly and inwardly inclined face 8 complementary to the under side 9 of the head 10 of the rail. The under side of the plate is provided with an upwardly and inwardly inclined surface 11 complementary to the top surface of the side or base flange 12 of the rail. Thus when the plate is moved bodily towards the rail when being secured thereto, the vertical arm 7 of the plate has a wedge-like action to hold the plate firmly united to the rail.

The lower arm 13 of the bar D extends laterally almost to the inner face 14 of the plate flange 4, and the end face 15 abuts the inner face or shoulder 16 of the bent over member 6.

The lower arm 13 of each plate is provided with an inwardly extending spike slot 17. Spikes 18 extend through the slots 17 of the bar D and through spike holes 5 in the plate C and into the ties B.

Fastening means.—Bolts E, preferably four in number, extend from opposite sides through suitable holes in the angle bars D and the rail web 19, and have on one end a head 20 and on the other end a nut 21. The head bears directly on one bar D while a suitable spring washer 22 on the bolt E, intermediate the other bar D and the nut 21, holds the nut in position.

It will thus be seen that the two rails A, A, are firmly joined end to end, by and clamped between the angle bars D; that the rail base flanges are held firmly in position by the bars D and the spikes 18, and that the tendency of the rails to shift or creep in one direction is resisted by the contact of the end of the L-bar D against one shoulder 16, motion in the opposite direction being resisted by the other shoulder 16. It will also be noted that the wave motion of the rail being compensated for by the camber or crowning of the rail bearing surface of the plate C, tendency to rattle is obviated.

In the use of most rail joints it is found that the rails are not properly kept in position; the "wave motion" of track produces a tendency to alternate up and down motion of the ends of the abutting rails and these ends become "battered" and damaged so that rail replacement becomes necessary. In the use of my rail joint this objection is entirely overcome. This is due mainly to the fact that the heavy load strain at the rail ends does not come separately thereon and then on the plate. By reason of the fact that the

rail base rests upon a high spot, i. e. on the crown of the cambered top surface of the plate,—the thrust is directed through the rails and the plate simultaneously.

Again, the tendency of the plate C to flex under train loads when the latter come upon the rails between ties, is counteracted and rendered negligible by the arched or truss formation of the plate C, which as shown in Fig. 1, is the result of the camber. It may be equally the result of making the plate C thicker or heavier between its ends.

Modifications and changes in details will readily suggest themselves to those skilled in the art, without departing from the principle of my invention as embraced in the appended claims, but after extensive tests and use in track under daily service conditions, I recommend as a preferred form of rail joint that illustrated and described herein.

I claim as my invention:

1. A rail joint comprising a channel plate of a length adapted to bear at its two ends upon adjacent ties, the rail bearing top surface of the plate being cambered longitudinally, an apertured angle bar on each side of the web of the rail, bolts extending through said bars and the web of the rails to secure the ends of adjacent rails to said bars, and spike holes in the plate for securing the joint to the ties of the road bed.

2. A rail joint comprising a channel plate adapted to bear for an appreciable distance at both ends upon two adjacent ties, the rail bearing top surface of the plate being cambered longitudinally, angle bars on opposite sides of the web of the rail, each bar being adapted to bear under the head of the rail and upon the top of the rail base flange, bolts extending through said bars to secure the ends of adjacent rails to said bars, and means for preventing relative movement between the rails, bars and plate.

3. A rail joint comprising a channel plate of a length adapted to bear upon two adjacent ties, the rail bearing top surface of the plate being cambered longitudinally, an angle bar on each side of the web of the rail, the lower member of the angle bar be-

ing recessed at its outer margin, bolts extending through said bars to secure the ends of adjacent rails thereto, and means for preventing relative movement between the rails, the bars and the plate, the plate being provided with spike holes which register with the angle bar marginal recesses.

4. A rail joint comprising a channel plate of a length to rest upon two ties, the rail bearing top surface of the plate being cambered longitudinally, a bar on each side of the web of the rail, bolts extending through said bars to secure the ends of adjacent rails to said bars, means for securing the rails, the bars and the plate to the ties of the road bed, and means on the plate coacting with the bars to prevent creeping of the rail lengthwise of the plate.

5. A rail joint comprising a channel plate of a length to rest upon two ties, the rail bearing top surface of the plate being cambered longitudinally, a bar on each side of the web of the rail, bolts extending through said bars to secure the ends of adjacent rails to said bars, means for securing the rails, the bars and the plate to the ties of the road bed, and means on the plate coacting with the bars to prevent creeping of the rail lengthwise of the plate, said means comprising an inwardly directed shoulder on the plate for contact with one end of the bars.

6. A rail joint comprising a channel plate of a length to rest upon two ties, the rail bearing top surface of the plate being cambered longitudinally, a bar on each side of the web of the rail, bolts extending through said bars to secure the ends of adjacent rails to said bars, means for securing the rails, the bars and the plate to the ties of the road bed, and means on the plate coacting with the bars to prevent creeping of the rail lengthwise of the plate, the end of the plate flange being cut and turned inwardly to form a shoulder for contact with the end of an angle bar.

In testimony, that I claim the foregoing as my invention I affix my signature this 29th day of October, 1925.

RICHARD T. SCHOLE.
